PLATE CLAMPING MECHANISM FOR
PRINTING PRESSES

Alfred Neef, Audubon, N. J.

Application June 10, 1948, Serial No. 32,090

3 Claims. (Cl. 101—378)

1

The present invention relates to improved means for securing curved stereotype and other curved plates to the rotary cylinder of printing machines and the like.

An important feature of the invention consists in providing the printing cylinder with spaced slots that extend longitudinally or axially thereof, and associating with the cylinder curved printing plates, and longitudinally spaced pairs of curved clips that extend circumferentially around the cylinder so as to firmly hold the plates against the printing cylinder. The clips constituting each pair are circumferentially aligned and have clamping blocks connected to the ends thereof so that two clamping blocks are connected or joined together by a clip. The clamping blocks are shaped so as to be slidably maintained in the longitudinal slots which are shaped to retain them radially thereon, and each slot receives a block of one of the pair of circumferentially aligned clips so that the blocks in each slot are movable separately or independently of each other.

Other objects and advantages of the invention will become apparent from the following description when taken in conjunction with the accompanying claims and drawings.

Referring to the drawings in which are shown several preferred embodiments the invention may assume:

Figure 1 is a side view of a printing cylinder with the invention associated therewith, and showing printing plates secured to one end of the cylinder.

Figure 2 is a detail side view of an end portion of the printing cylinder.

Figure 3 is a sectional view taken substantially along the line 3—3 of Figure 2.

Figure 4 is a sectional view taken substantially along the line 4—4 of Figure 1.

Figure 5 is a sectional view taken substantially along the line 5—5 of Figure 1.

Figure 6 is a sectional view taken substantially along the line 6—6 of Figure 5.

Figure 7 is a sectional view taken substantially along the line 7—7 of Figure 1.

Figure 8 is a detail perspective view of the plate blocks.

Figure 9 is a perspective view of a pair of clips and their associated clamping blocks.

Figure 10 is an enlarged sectional view taken substantially along the line 10—10 of Figure 1.

Figure 11 is an enlarged sectional view taken substantially along the line 11—11 of Figure 1.

Figure 12 is an enlarged sectional view taken along the line 12—12 of Figure 1.

2

Figure 13 is a sectional view similar to Figure 12 of a modified form of the invention.

Figure 14 is a plan view of the left-hand portion of Figure 1, with the plates removed, and

Figure 15 is a detail view of the retaining nut and its associated parts.

Referring to the drawings, 10 indicates a rotary printing cylinder such as employed in newspaper printing machines and the like, and is preferably formed with diametrically opposed substantially T-shaped slots 11 between which are arranged to be positioned a plurality of curved or segmental printing plates 12. As shown, the cylinder is of such length as to carry eight printing plates which are arranged in horizontal and circumferentially spaced rows so as to extend around the cylinder in spaced pairs. It will, of course, be manifest that the size and number of plates employed may be varied as particular printing conditions may require. In order to firmly hold each of the plates 12 in a fixed position on the cylinder, there is associated with the longitudinal side edges of the plates, retaining clips or members 13 which are arranged in circumferentially aligned pairs 14, 15 and 16 (Fig. 1) that extend around the cylinder 10, and are provided with opposed beveled or inclined surfaces 17 (Fig. 12) so as to frictionally engage the complementary formed beveled edges 18 on the adjacent sides of the plates 12 to prevent longitudinal movement of the plates when carried by the cylinder. The clips 13 at each end thereof preferably are integrally connected to clamping blocks 19 (Fig. 9) which extend longitudinally or substantially at right angles to the clips. Each of the blocks 19 may be of channel or angular shape and has an outwardly extending flange 20 at the bottom or lower end thereof and a tapered flange 21 extending from its upper end and in the same direction as the flange 20. Thus, it will be seen that a curved clip 13 is positioned between a pair of blocks 19 and preferably is connected centrally to a tapered flange 21 so as to be flush with the top surface of the block. Of course, the clips 13 instead of being integral with the blocks 19, may be detachably connected thereto in any suitable manner. The centrally disposed pair of clips 15 (Fig. 10) are formed with threaded inclined openings 22 through which extend the threaded bolts 23 that engage the adjacent sides 24 of the slots 11 so as to maintain the center clips in a fixed position. The pairs of clips 14 and 16 on opposite sides of the center clips 15, constitute intermediate retaining means which coact with the center clips for maintaining the adjacent intermediate plates 12 on the cyl-

inder. Additionally, outer pairs of clips 25 and 26 (Fig. 1) are connected to opposite ends of the cylinder 10 so as to coact with the intermediate clips 14 and 16 respectively, for retaining the end plates 12 in position when the parts are set up. Each of the outer clips 25 and 26 is preferably wider than the clips 13, and terminate at their ends in clamping blocks 27 that extend inwardly of the cylinder and are of substantially the same shape as the blocks 19 so as to be slidably mounted in the slots 11 (Fig. 11). Each of the end clips 25 and 26 between the clamping blocks 27 (Fig. 7) may be provided with a T-shaped slot or the like 28 that is slidable in a complementary T-shaped slot or groove 29 in the outer periphery of the cylinder 10 between the slots 11. Each of the blocks 28 has a longitudinally extending threaded opening 30 (Fig. 6) which registers with an opening in the annular end member or plate 31. A retaining threaded bolt 32 extends through the aligned openings into the slot 29 and has a collar or flange 33 that bears against the side of the cylinder 10 and is positioned between the member 31 and the end of the cylinder. The outer threaded end 34 of the bolt receives a nut 35 so that upon rotation of the bolt, the block 28 and its associated clip 25 may be moved axially to any desired position so as to insure a firm engagement with the adjacent end of a press plate (Fig. 14). The intermediate pairs of clips 14 and 16, and the end clips 25 and 26 may be formed with threaded openings 36 (Fig. 10) for receiving set screws 37 that fit into spaced threaded recesses 38 in the outer periphery of the cylinder 10 for releasably securing the clips 13 to the cylinder. The pair of blocks 19 (Fig. 5) which slide in the same T-shaped slot 11 are spaced from each other to permit independent movement of these blocks in the slot. The pair of end blocks 27 in the same slot are likewise spaced so that they may be moved toward and away from each other. The clamping blocks 19 on the center clips 15 slide easily into place and then are tightened by the set screws 23 which move the blocks closer together and firmly maintain the center clips 15 in position on the cylinder. The blocks 28 are positioned relative to the end clips 25 and 26 so as to insure the intermediate portions of the clips being firmly secured to the cylinder.

Slidably mounted in the slots 11 between the clamping blocks 19 are channel-shaped plate blocks 38 which are substantially similar in shape to the blocks 19 (Fig. 8) and have their upper beveled edges 39 engaging the adjacent sides or ends of the plates 12 to prevent rotation of the plates relative to the cylinder. The horizontal blocks 38 coact with the transverse clips 13 for firmly maintaining the plates in a fixed position on the rotary printing cylinder 10. The ends of the blocks 38 may be provided with recesses 40 for receiving coil springs 41 that abut against the adjacent sides of the clamping blocks 19 and 27 so that when the parts are assembled and the screws 23 and 32 tightened, the press plates are firmly maintained on the cylinder, and the springs 41 will simultaneously be tightened between the block and thus provide a positive but yieldable means for insuring the plates 12 being retained in a fixed position.

When the clips 13 are used with plates having narrow margins, they are preferably of triangular shape in cross section as shown in Figure 12, and extend the length of the adjacent abutting sides of the plates 12. If the plates 12 are required

to have wider margins, then the clips 13 may be formed as shown in Figure 13, having the opposed sides formed with downwardly inclined portions 42 which terminate at their lower ends in straight portions 43 so as to coact with the similarly shaped opposed sides of the plates 12. The ends of the printing plate 12 which abut the clips 13 may be trimmed or reduced to provide a small margin between the print on each of the plates 12 and their confining clips 13 so as to avoid cutting unintentionally into the printing on the press plates, and without the necessity of increasing the marginal width between printed pages, thus permitting the use of relatively small or narrow clips for retaining the plates on the printing cylinder.

It will be noted that the clips 13 extend laterally from the upper flanges 20 of the clamping blocks 19 so that when the blocks are inserted in the slots 11, the inclined opposed surfaces of the clips 13 will engage the adjacent sides or ends of the plates 12 throughout the width thereof, and the inclined flanges 21 of the blocks will be free from engagement with the ends of the plates engaged by the clips 13 so that each clip projects along the entire width of the press plate 12 and abuts or overlaps the same to hold the printing press plate firmly on the cylinder. By connecting the depending blocks 19 to the ends of the curved clips 13, means are provided for preventing the ends of the clips 13 from tilting upwardly when the printing cylinder is in operation.

The use of such narrow clips not only means less width for the paper roll used in printing but also requires less tonnage of printing paper. Moreover, the length and depth of the clips 13 are such as to engage the adjacent sides of the press plates throughout the entire depth of the plates and provides releasable clamping means that engage the plates the full width of the clips. The clips 13 may be of such size and shape to fit margins as required, and are formed of minimum width to insure safety and provide the necessary hold for maintaining the printing press plates securely on the cylinder. The clamping blocks 19 and the plate blocks 38 may be inserted separately in the grooves 11 when assembling the machine so as to be properly positioned relative to the plates to be retained on the cylinder. As it will be seen from Figure 12, the clip 13 gives a margin as narrow as the top of the clip and this width of margin may vary depending on the particular size plates and the purpose for which the machine is to be used.

While for practical purposes it has been found that it is necessary only to provide two diametrically opposed T-shaped slots 11 in the cylinders 10, thus reducing to a minimum the number of such slots, it will be manifest if smaller sizes of plates are required, which dispense with the center blocks 28 that additional spaced slots 11 may be formed in the cylinder for receiving such blocks.

Thus, it will be seen that the clips 13, 25 and 26 and their associated parts provide simple, efficient and positive means for engaging the entire side of the printing plates in order to hold them on the cylinder. Moreover, the clips can be varied in size or shape to fit different shapes of plate edges as printing conditions may require. Further, the clips may be reduced to a minimum of width for safety in holding press plates in position without impairing the printing efficiency of the machine.

It will be understood that the forms of the in-

vention shown are merely illustrative and that such changes may be made without departing from the spirit of the invention as fall within the scope of the following claims.

I claim:

1. In combination with a printing machine, a printing cylinder having diametrically opposed substantially T-shaped slots extending longitudinally thereof and coextensive in length therewith, curved printing plates spaced longitudinally and circumferentially on said cylinder to provide pairs of intermediate plates and end plates, a pair of substantially centrally disposed curved clips engaging the adjacent sides of the intermediate plates, the central clips terminating at their ends in flanged clamping blocks slidably mounted in said longitudinal slots, means securing the central clips in a fixed position on the cylinder, a pair of intermediate curved clips on each side of the center clips and engaging the adjacent edges of the intermediate plates and the end plates, said intermediate clips terminating in flanged clamping blocks slidably mounted in said longitudinal slots, curved end clips engaging the outer end of the end plates and provided with flanged end blocks slidable in said longitudinal slots, each pair of clips being arranged so that a clip thereof has a block slidable in the same slot as its associated clip, and pairs of plate blocks slidably mounted in each of said slots between clamping blocks for engaging the sides of the plates.

2. A printing machine as called for in claim

1 and having yieldable means interposed between the plate blocks and the clamping blocks.

3. In combination with a printing cylinder having spaced T-shaped slots in the outer surface thereof, a printing plate carried by the cylinder, means for firmly securing the edges of the plate to the cylinder, said means including curved clips extending circumferentially around the cylinder and having beveled edges engaging the edges of the plate, each of said clips having its ends terminating in flanged clamping blocks slidable in said slots, and plate blocks slidably mounted in said slots between the clamping blocks for engaging the sides of the plate and coacting with said clips for maintaining the plate in a fixed position on the cylinder.
